UNITED STATES PATENT OFFICE.

JOHN W. FORCE, OF WICHITA FALLS, TEXAS.

CLEANING DEVICE FOR OIL TANKS AND THE LIKE.

Application filed May 10, 1927. Serial No. 190,233.

My invention relates to tank cleaning devices and more particularly to the treating of petroleum emulsions and removing the impurities after treatment has been applied; 5 and the object is to provide devices for applying treating fluids and then thoroughly agitating the treating fluids and the contents of the tank or receptacle and also to provide heating means to be applied during the agitation of the liquids. Another object is 10 to provide two sets of agitating means or apparatus which can be used separately or in combination to meet the various conditions found in actual service. Another object is 15 to provide apparatus which is adapted both for agitating the liquids and for removing base settling and all sludge from the receptacles. One object of this invention is to purify petroleum and various liquids, such 20 as water treating, churning, washing, mixing of paints, and other operations in the industrial arts. Other objects and advantages will be fully explained in the following description and the invention will be 25 more particularly pointed out in the claims.

Reference is had to the accompanying drawings which form a part of this application.

Fig. 1 is a vertical section of a tank and 30 vertical sections of the two agitating devices.

Fig. 2 is a vertical section of a tank and a vertical section of one agitating device and showing a variation in the agitating device.

35 Fig. 3 is a plan view of the upper agitating devices.

Fig. 4 is a broken vertical section of a tank, showing the lower agitating devices, partly in section.

40 Fig. 5 is a plan view of the lower agitating devices.

Fig. 6 is a broken view, showing a variation in the agitators which are attached to the bottom of the tank.

45 Similar characters of reference are used to indicate the same parts throughout the several views.

A section of a tank or receptacle 1 is shown in the drawings and a central hollow intake 50 pipe 2 is anchored to the bottom of the tank by means of a casting or bracket 3, but the pipe 2 does not extend entirely to the bottom, leaving an exit from the pipe into the space within the tank so that the tank may 55 be filled with oil or with a treating fluid or other fluid let into the tank and by

which fluids and impurities may be forced out of the tank, as hereinafter explained.

Upper and lower agitating devices are 60 provided. The lower agitating devices include a gear wheel 4 which is rotatable about the spindle 2 and this gear wheel 4 is driven by a pinion 5 which is driven by a shaft 6. A cone-shaped spreader 8 is attached to the gear wheel 4 and agitators 9 are attached to the spreader 8 and wheel 4. The agitators 9 are so shaped as to sweep impurities under the pipe 2. The impurities are removed through a discharge pipe 10. When the cock 11 is opened, the pressure of the fluid in the tank will force the impurities out through the pipe 10, the impurities being brought under the lower end of the pipe 2.

The tank cleaner is provided with an upper set of agitating devices including a gear wheel 12 which is loosely mounted on the pipe 2. The gear wheel 12 is driven by a pinion 13 which is rigid with the shaft 14. An open-bottom cylinder 15 is rigid with the gear wheel 12 and is provided with vanes 16. The object of the vanes 16 is to elevate the liquids through the cylinder 15. A plurality of discharge vanes 17 is provided and these vanes 17 are interposed between disks 18, the object being to throw liquids 85 out at different angles or elevations. The upper agitating devices will be driven by the gear wheels 12 and 13 and the shaft 14.

Variations are shown in Fig. 2 of the drawings. The vanes 19 are attached to the bottom of the tank. The vanes 19 are similar in shape to the vanes or agitators 9. When the fluid in the tank is given rotary motion by the agitators in the upper part of the tank, the impurities will be brought under the pipe 2 because of the particular curvature of the vanes 19. The cylinder 20 is shown to be telescopic instead of the form shown in Fig. 1. One set of agitating or discharge vanes 21 is shown disposed between two disks 22. The driving gears for the agitating devices shown in Fig. 2 are placed above the agitating devices and connected thereto by a sleeve 23 which is rigid with the gear wheel 12 and with the cylinder 20.

The lower agitating devices shown in Figs. 4 and 5 are adapted for use independently of the agitating devices illustrated in the upper parts of Figs. 1 and 2. The devices of Figs. 4 and 5 are necessary for successful operation of the devices shown in the upper parts of Figs. 1 and 2. Short vanes

24 are formed on extensions from the lower disk 22 for driving the fluid downwardly, thereby co-operating with the vanes 21.

What I claim, is,—

- 5 1. A device of the character described comprising a central hollow receiving and discharge spindle, a discharge pipe communicating with said spindle, a cone-shaped spreader rotatable about said spindle, means 45 for spacing said spindle from the bottom of a tank, a gear wheel rigid with said spreader, and means for driving said gear wheel.
- 10 2. A device of the character described comprising in a liquid containing tank a central hollow spindle constituting a receiving and discharge pipe, means for anchoring said spindle to and above the bottom of said tank, a cone-shaped spreader rotatable 50 about said spindle, agitators rigid with said spreader, a gear wheel rigid with said spreader, and means for driving said spreader gear wheel.
- 15 3. A device of the character described comprising in a liquid containing tank a central hollow spindle constituting a receiving and discharge pipe, means for anchoring said spindle to the bottom of said tank but spacing said spindle from the bottom 55 of the tank, a cone-shaped spreader rotatable about said spindle, gearing for rotating said spreader, agitators carried by said spreader for sweeping on the bottom of said tank and forcing impurities under said spindle, and a discharge pipe communicating 60 with said spindle.
- 20 4. A device of the character described for a liquid containing tank comprising a hollow spindle constituting a receiving and 65 discharge pipe, means for anchoring said

spindle to and above the bottom of said tank, spreading and agitating means carried by said spindle, means for driving said spreader, liquid elevating and mixing means rotatable about said spindle, and means for 45 driving said rotatable and mixing means.

5. A device of the character described for a liquid containing tank comprising a hollow spindle constituting a receiving and discharge pipe, means for anchoring said spindle to and above the bottom of said tank, a spreader and agitating means carried by said spindle, means for driving said spreader, liquid elevating and mixing means rotatable about said spindle consisting of an open-bottom cylinder and vanes carried in the lower end thereof, spreading vanes carried by the upper end thereof, a discharge pipe for said spindle and means for driving said cylinder and vanes. 55

6. A device of the character described for a liquid containing tank comprising a hollow spindle constituting a receiving and discharge pipe, means for anchoring said spindle to and above the bottom of said tank, 65 spreading means rotatable about said spindle, means for forcing impurities under the lower end of said spindle, liquid elevating and mixing means carried by said spindle and rotatable about said spindle consisting of an open-bottom cylinder having 70 elevating vanes in the lower end thereof and radially and downwardly spreading vanes carried on the upper end of said cylinder, means for rotating said cylinder, and 75 a discharge pipe for said spindle.

In testimony whereof, I set my hand, this 19th day of March, 1927.

JOHN W. FORCE.
